GOODRICH Q. LEWIS, OF WASHINGTON, DISTRICT OF COLUMBIA, ASSIGNOR TO WILLIAM H. MINER, OF CHAZY, NEW YORK.

HIGH-CAPACITY FRICTION SHOCK-ABSORBING MECHANISM.

1,303,338.

Specification of Letters Patent. Patented May 13, 1919.

Application filed June 3, 1918. Serial No. 237,840.

To all whom it may concern:

Be it known that I, GOODRICH Q. LEWIS, a citizen of the United States, residing at Washington, in the District of Columbia, 5 United States of America, have invented a certain new and useful Improvement in High-Capacity Friction Shock-Absorbing Mechanisms, of which the following is a full, clear, concise, and exact description, reference being had to the accompanying drawings, forming a part of this specification.

This invention relates to improvements in high capacity friction shock absorbing mechanisms.

15 The object of the invention is to provide a frictional shock absorbing mechanism, more particularly designed for railway draft riggings and which is of exceedingly high capacity, the parts being compactly arranged.

20 In the drawing forming a part of this specification, Figure 1 is a part side elevational, part vertical, longitudinal section of a portion of a railway car showing my improvements applied thereto. And Figs. 2 25 and 3 are vertical, transverse, sectional views taken on the lines 2—2 and 3—3, respectively, of Fig. 1.

In said drawing, 10—10 denote channel-shaped center or draft sills of usual form 30 and spaced the standard distance apart, said sills having secured to their inner faces front stops 12 and a rear abutment block or casting 13 which extends from sill to sill and is secured to both. Said block 13 forms a rear 35 stop or abutment for the gear, as will be understood. The draw bar 14 of the rigging is adapted to be operatively secured to the shock absorbing mechanism proper by a suitable yoke which, in the instance shown, comprises a pair of horizontal loop-shaped yoke 40 elements 15 and 15. Said horizontal yoke elements 15 are arranged as clearly shown in Figs. 1 and 2, that is, one at the upper portion of the draft gear and the other at the

45 lower portion and each of said yoke members 15 is provided at its forward end with a pair of wings 16 which overlap each other and the butt of the draw bar and are keyed to the latter, as by a coupler-key 17.

50 Each of said yoke members 15 is further provided with a transverse shoulder or gib 18 adapted to coöperate with the usual shoulders of the draw bar butt. A front follower 19 is employed with the draft rigging and the shock absorbing mechanism

and rear ends of the yoke are supported by a detachable saddle plate 20.

Referring now more particularly to the shock absorbing mechanism proper, the same includes a casting A formed at its front end 60 with vertical twin-arranged friction shells 21 and 22. Coöperable with each of the shells 21 and 22 is a series of friction shoes 23 and wedge 24 with anti-friction rollers 25 interposed between the shoes and wedge 65 in a well known manner. To the rear of the shells 21 and 22, the casting A is enlarged both vertically and horizontally to accommodate an unusually heavy main spring resistance. The casting A is formed with an 70 upper cylindrical portion 26 and a corresponding lower cylindrical portion 27 with horizontal flanges 28—28 at the sides, said casting being open at the sides between said flanges 28 to permit insertion of the springs. 75 As will be understood, the casting A has an integral rear wall 29.

The structure of the casting A at the rear of the shells 21 and 22 is so designed that all of the springs may be introduced through 80 the open sides and two springs 30 and 31 are first introduced and are seated in the spring pockets provided by the cylindrical sections 26 and 27, respectively. Thereupon the remaining two springs 32 and 33 are introduced, one from each side. As clearly appears from Fig. 3, with the arrangement shown, I am enabled to employ four of the usual standard springs employed with friction gears, due to the fact that two of the 85 springs are arranged horizontally side by side and occupy substantially the full width between the standardly spaced sills, and the other two springs are placed one above the other below, so that the entire arrangement 90 may be mounted within the usual space found on railway cars.

A follower 34 is mounted within the casting A at the front ends of the four springs 30, 31, 32 and 33, said follower 34 having a 100 pair of annular flanges 35 slidably fitting within the cylinders 21 and 22. Said annular flanges 35 serve to form pockets to receive the rear ends of preliminary springs 36 which are interposed between each set of 105 friction elements and the follower 34. Retaining bolts 37—37 are used with each set of friction elements to hold the latter in assembled position in the shock absorbing mechanism,

With the arrangement above described, it is evident that I have provided a twin friction shock absorbing mechanism of exceedingly high capacity and which is at the same time adapted to be mounted between stand-
ardly spaced sills and is not of excessive height. By disposing the cylindrical portions 26 and 27 of the casting A with respect to the horizontal flange portions 28, as here-
inbefore described, I thereby leave the necessary space to receive the side arms of the two yoke members 15 and avoid undue over-all width or undue height of the shock absorbing mechanism and yoke when the latter are
assembled.

I claim:

1. In a friction draft rigging, the combination with draft sills, front and rear stops, a draw bar, and yoke-acting means; of a friction shock absorbing mechanism including a main spring resistance, the latter comprising four coils, two of said coils being arranged horizontally side by side and occupying substantially the full width between the sills, the other two coils being located one above and the other below the first mentioned two coils.

2. In a draft rigging, the combination with draft sills spaced a standard distance apart, of a twin friction shock absorbing mechanism mounted between said sills; said shock absorbing mechanism including two vertical twin-arranged friction shells with coöperating friction elements; and four main

springs, two of said main springs being arranged with their axes parallel in a vertical plane and the other two main springs being arranged parallel with their axes in a horizontal plane.

3. As an article of manufacture, a casting for friction shock absorbing mechanism, said casting including a pair of friction shells arranged side by side and a spring casing, said casing including upper and lower cylindrical portions adapted to form two spring seats, said casing being open at the sides to thereby permit insertion of springs there-
through.

4. In a draft rigging, the combination with draft sills, front and rear stops, and a draw bar, of a friction shock absorbing mechanism having a spring cage, said spring cage in its central portion being of substantially the same width as the spacing between said sills and having upper and lower sections of narrower width; and a two-part yoke adapted to connect the shock absorbing mechanism with the draw bar, said two-part yoke comprising upper and lower horizontal loops adapted to straddle said upper and lower portions of said casing.

In witness that I claim the following I have hereunto subscribed my name this 24th day of May 1918.

GOODRICH Q. LEWIS.

Witness:

GEO. F. GRAHAM.
